UNITED STATES PATENT OFFICE.

HENRY K. HARKER, OF CINCINNATI, OHIO, ASSIGNOR OF THREE-FOURTHS
TO JOHN H. DAVIS AND WILLIAM D. BEGGS, BOTH OF SAME PLACE.

PENCIL-SHARPENER.

SPECIFICATION forming part of Letters Patent No. 481,517, dated July 1, 1890.

Application filed July 22, 1889. Serial No. 318,268. (No model.)

To all whom it may concern:

Be it known that I, HENRY K. HARKER, of Cincinnati, in the county of Hamilton and State of Ohio, have invented certain new and useful Improvements in Pencil-Sharpener; and I do hereby declare the following to be a full, clear, and exact description of the same, reference being had to the accompanying drawings, forming a part of this specification, and to the letters of reference marked thereon.

My invention has for its object to provide an improved appliance for sharpening pencils which shall be simple in construction and efficient in operation, and whose cost of manufacture shall be so small as to enable it to be sold at a price which will bring it within the reach of all.

Most pencil-sharpener heretofore made have either been so expensive as to render their general adoption impracticable, or else, in order that they might be sold at a low price, they have been so fragile or imperfectly made as to cause them to soon wear out and become inoperative and useless.

In the construction of my improved appliance I have endeavored to employ only such instrumentalities as cannot easily get out of order and as will last for years without material deterioration.

The essential elements of my appliance are, first, a stationary abrading-surface consisting, preferably, of a coarse steel file; secondly, a holder for the pencil, provided with a friction-disk by which to give it rotation when said disk is pressed against a suitable surface, and, thirdly, a handle in which the pencil-holder is mounted, and by which said holder is moved back and forth while it is revolved by the operation of its friction-disk, and while the pencil held by it is being rubbed back and forth over the abrading-surface. The friction-disk on the holder being of much greater diameter than the pencil held by the holder, it follows that when the said disk is in contact with its co-operating friction-surface and the pencil is at the same time in contact with the abrading-surface a back-and-forth motion of the holder will not only cause the pencil to revolve, but also, by reason of the difference in the diameters, to be slid or dragged over the abrading-surface, thereby causing the end

of the pencil to be reduced to a conical form, or, in other words, to be brought to an ideal point. The holder is so constructed that it will hold the pencil tightly within it while being acted upon, and yet will permit of the longitudinal adjustment of the pencil, so as to enable a point of greater or less length to be formed.

In order to maintain during the sharpening operation a proper relation between the holder and the abrading-surface or file, I preferably cause the friction-disk of the holder to travel in a guiding track or groove, and for the purpose of increasing the friction on said disk and preventing it from slipping I preferably insert a strip of rubber or other equivalent material in the bottom of said track or groove.

The abrading-surface or file and the guide track or groove may be mounted upon a suitable base-block, or they may be arranged within a small box or "scholar's companion," that is adapted to receive not only the pencil-holder and handle, but also pencils, pens, rubber, and other like articles, such as school children are required to be supplied with.

In the accompanying drawings, Figure 1 represents a top plan view of my invention; Fig. 2, an end view of the same; Fig. 3, a sectional view taken longitudinally of the holder, and Fig. 4 a perspective view of the invention as applied to a scholar's companion.

Similar letters of reference in the several figures indicate the same parts.

A represents a coarse steel file composing the abrading or cutting surface; B, the holder, consisting of a sleeve provided with a friction-disk C, and having one end slotted or split, as shown at b, so as to tightly grasp and hold the pencil E when pushed into it.

F is the handle, provided with a hollow bearing f, in which the holder proper is mounted so as to rotate freely, longitudinally slipping between the two being prevented by means of a pin or screw G, passed through the bearing and into an annular groove H, formed in the holder, as shown in Fig. 3. Other modes of preventing the longitudinal movement may be adopted; but I prefer the one described on account of its simplicity and cheapness.

I represents the groove or track in which the friction-disk of the holder is guided, and

K the strip of rubber employed for the purpose of increasing the friction on said disk.

To sharpen pencils with this appliance, it is only necessary that the pencil be pushed 5 through the holder, as shown in Fig. 1, and then that the handle be grasped and the friction-disk be inserted in the guide groove or track and there held while the holder is moved back and forth in such manner as to bring 10 the end of the pencil in contact with the abrading-surface or file, the sharpening operation being performed in much less time than it could be done by a penknife and the quality of the work being much better.

15 In the modification shown in Fig. 4 the abrading-surface or file A' is secured at one side of the box and the guide groove or track I' at the other, a suitable compartment L being arranged between the two for receiving 20 the holder and its handle.

I claim as my invention—

1. In a pencil-sharpener, the combination, with the holder for clamping the pencil, having a friction-disk thereon, of an independent 25 and movable handle, in which said holder is journaled, substantially as described.

2. In a pencil-sharpener, the combination,

with an abrading-surface for the pencil and a friction-surface adjacent thereto, of a pencil-holder having a friction-disk co-operating 30 with the friction-surface and an independent and movable handle, in which the pencil-holder is journaled, substantially as described.

3. In a pencil-sharpener, the combination, with an extended abrading-surface for the 35 pencil and a guide adjacent to and parallel therewith, of an independent holder for the pencil, having a disk mounted rigidly thereon for engaging the guide, and an independent and movable handle, in which said holder is 40 journaled, substantially as described.

4. In a pencil-sharpener, the combination, with an abrading-surface for the pencil and a guide adjacent to and parallel therewith, of a holder for the pencil, having a relatively 45 large disk rigidly mounted thereon for engaging the guide to rotate the pencil slowly, and an independent handle, in which said holder is journaled, substantially as described.

HENRY K. HARKER.
